CLAIM

I claim the ornamental design for a lighting fixture, as shown and described.

DESCRIPTION

FIGS. 1-7 are drawings of a first embodiment of the lighting fixture.

FIG. 1 is a top view of the fixture,
FIG. 2 is a top perspective view,
FIG. 3 is a left side view,
FIG. 4 is a front view,
FIG. 5 is a right side view,
FIG. 6 is a bottom view and
FIG. 7 is a bottom perspective view.

FIGS. 8-15 are drawings of a second embodiment of the lighting fixture.

FIG. 8 is a top view of the fixture,
FIG. 9 is a bottom view,
FIG. 10 is a left side view,
FIG. 11 is a front view,
FIG. 12 is a right side view,
FIG. 13 is a rear view,
FIG. 14 is a top perspective view and
FIG. 15 is a bottom perspective view.

FIGS. 16-23 are drawings of a third embodiment of the lighting fixture.

FIG. 16 is a top view of the fixture,
FIG. 17 is a bottom view,
FIG. 18 is a left side view,
FIG. 19 is a front view,
FIG. 20 is a right side view,
FIG. 21 is a rear view

FIG. 22 is a top perspective view and
FIG. 23 is a bottom perspective view.

FIGS. 24-30 are drawings of a fourth embodiment of the lighting fixture.

FIG. 24 is a top view of the fixture,
FIG. 25 is a bottom view,
FIG. 26 is a left side view,
FIG. 27 is a front view,
FIG. 28 is a right side view,

(Continued)

FIG. 29 is a top perspective view and FIG. 30 is a bottom perspective view; and, FIGS. 31-37 are drawings of a fifth embodiment of the lighting fixture. FIG. 31 is a top view of the fixture, FIG. 32 is a bottom view, FIG. 33 is a left side view, FIG. 34 is a front view, FIG. 35 is a right side view, FIG. 36 is a top perspective view; and, FIG. 37 is a bottom perspective view. Broken lines in the drawings illustrate features of the lighting fixture that form no part of the claimed design. Dot-dash lines in the drawings represent boundaries of the claimed design and form no part thereof.
